UNITED STATES PATENT OFFICE

2,568,478

WRIST PIN RETAINER

Glenn D. Angle, Thomaston, Conn., assignor to
The New Britain Machine Company, New
Britain, Conn., a corporation of Connecticut

Application October 23, 1946, Serial No. 705,187

3 Claims. (Cl. 74—580)

1

My invention relates to reciprocating engines and in particular to improved means for retaining in place the wrist pins carried by a big-end or cluster for coupling a plurality of connecting rods to a crankshaft. In radial-type engines the invention is particularly applicable to the articulated system employing a so-called solid-ring big-end, but it will be clear that advantageous results may be obtained by its application to split and other big-end constructions.

It is an object of my invention to provide an improved means for retaining wrist pins in place in an engine of the character indicated.

It is another object to provide improved means for locking wrist pins against both angular and axial movement, within the space limitations common to the above-indicated constructions, and without adding undesirable weight or introducing difficult assembly problems.

It is a further object to provide an improved wrist-pin retainer that may be considered fool-proof, that is, which will be practically impossible to install incorrectly.

It is, in general, an object of my invention to provide an improved wrist-pin retainer that will be light in weight, compact, inexpensive to fabricate, efficient, and simple to assemble.

Other objects and various further features of the invention will hereinafter be pointed out or will occur to those skilled in the art from a reading of the following specification in conjunction with the accompanying drawings, in which:

Fig. 1 is a fragmentary vertical sectional view of a five-cylinder radial engine showing a big-end or connecting-rod cluster to which my invention has been applied;

Fig. 2 is an enlarged fragmentary sectional view taken substantially in the plane 2—2 of Fig. 1;

Fig. 3 is an enlarged fragmentary sectional view taken substantially in the plane 3—3 of Fig. 1;

Fig. 4 is an end elevation in partial section of the cluster shown in Fig. 1;

Fig. 5 is an elevation of the wrist-pin retainer shown in Fig. 1;

Fig. 6 is a sectional view illustrating a wrist pin according to the invention, as shown in Fig. 1; and

Fig. 7 is an enlarged fragmentary view illustrating in more detail the function of my invention.

Broadly speaking, my invention contemplates wrist-pin-retainer means engageable with an end of a connecting-rod cluster and so abutting parts

2

of the wrist pins as to retain them against both axial and rotational displacement. In the specific form to be described, the retainer is secured to the cluster by means of a bayonet-type engagement, whereby a partial rotation of the retainer with respect to the cluster may effect locking engagement against axial displacement. Once so locked, a portion of the retainer may be deformed to fit in a recess within the cluster where-by rotational dislodgment of the retainer is resisted. The wrist pins include longitudinal projections extending beyond the ends of the cluster, and these projections are eccentrically offset from the axes of the wrist pins. When the retainer is secured in place, these eccentric projections may abut the retainer to prevent wrist-pin rotation. Since part of the retainer radially overlaps portions of the wrist pins, axial displacement of the wrist pins is also prevented.

Referring to the drawings, my invention is shown in application to a radial engine 10 having five cylinders 11. The pistons 12 within these cylinders reciprocate to drive a crankshaft 13 about a central axis of rotation 14. Various means may be employed for connecting the pistons to the crankshaft, but in the form shown, a so-called solid big-end 15 pivotally carries four link-type connecting rods 16 and is lockingly secured to a master connecting rod 17. Wrist pins 18 passing through the cluster 15 and the ends of the connecting rods 16 and 17 serve to tie the described parts together. The parts which have thus far been described are well known in the art and, therefore, form no part of the present invention.

In accordance with the invention, I have provided a novel wrist-pin retainer 19 for securely holding all the wrist pins 18 in place (that is, against axial displacement) and also for preventing rotation of the wrist pins 18 about their own axes. The retainer ring 19 is engageable with an end of the cluster 15, and it also abuts each of the wrist pins 18. In the form shown, locking engagement of the retainer 19 with the cluster 15 is of the so-called bayonet-type, that is, radially extending flanges or projections 20 on the retainer are insertable through corresponding recesses 21 in the cluster 15, and the retainer 19 may then be partially rotated within an annular groove 22 to effect a secure locking against axial displacement of the retainer 19. To secure the retainer 19 against rotational dislodgment, the retainer 19 may also include a radially extending tab or other deformable portion 23 which will overstand an appropriately shaped recess 24 in

the cluster 15 when the parts are in their bayonet-locking position. It is clear that slight deformation of the tab 23, as by tapping with a hammer, will cause secure engagement within the recess 24 so as to prevent dislocation of the bayonet lock while the engine is in use.

In the form shown, the groove 22 which accommodates the retainer ring 19 extends radially inwardly and is defined by the space between the main body of the cluster 15 and a radially outwardly extending flange 25. Preferably, the flange 25 extends radially to an extent intermediate the innermost and outermost extremes of the wrist-pin-receiving bores 26 and of other longitudinally extending apertures 27 (provided in the cluster 15 for purposes of reducing weight). It will be clear that in the process of boring the cluster, arcuate discontinuities (as at 21) will be formed in the otherwise circumferentially continuous lip of the flange 25.

In accordance with the invention, the retainer ring 19 is formed on its inner surface with a plurality of arcuate lobes or projections 20 so shaped and placed that the ring 19 may be axially inserted past the flange 25—the lobes 20 passing through the arcuate recesses 21. Upon subsequent rotation (clockwise, in the sense of Fig. 1) of the retainer 19 to effect the bayonet-type locking engagement, it will be clear that the lobe 20 will engage the flange 25 securely against axial displacement. When in this locked position the tab 23 may be tapped inwardly to set in one of the recesses 24, in order to give permanency to the engagement (see Fig. 7). If desired, a saving in weight may be effected by piercing the ring 19 with a plurality of apertures 26—one preferably adjacent each of the lobes 20.

In accordance with a feature of the invention, the disposition of wrist-pin-receiving bores 26 and of weight-saving bores 27 is such as to be symmetrical about a plane passing through the axis of the cluster 15. In the form shown, this plane of symmetry is vertical, passing between the two bores 26 for the master connecting rod 17, and through the axis of the lowermost weight-reducing bore 27. With this arrangement the retainer ring 19 will also have symmetrically disposed locking lobes 20, so that the retainer 19 may be said to be reversibly insertable upon the cluster 15—in other words, there would then be no wrong way to face the retainer 19 against the side of the cluster 15.

It has been indicated that in accordance with the invention the wrist pins 18 are preferably formed with longitudinal extensions projecting beyond the end of the main body of the cluster 15 so as to engage the outer periphery of the retainer 19 and thereby to prevent rotation of the wrist pins about their axes. As shown in Figs. 6 and 7, these projections 30 are preferably so formed that they will abut the retainer ring 19 with a minimum of angular displacement (with respect to the axis of the wrist pin 18). In the form shown, the wrist pin 18 is generally annular in shape with a circular closure disc 21 seated on a shoulder at each end of the wrist pin. The projections 30 are defined on their outer surfaces by continuations of the outer surfaces of wrist pin 18 and on their inner surfaces 32 by arcuate lands of substantially the same radius as the outer edge of the retainer ring 19. The lands 32 are preferably so positioned that the projections 30 may be said to be substantially semi-cylindrical. The fit which results from this construction will

be understood to permit a minimum of rotational play to the wrist pin and also to provide wear resistance for a prolonged period.

Although I have described the invention as applied to a circumferentially continuous retainer having a bayonet-type lock along its inner edge, it is clear that the principles of the invention are equally applicable to equivalent forms. For example, the cluster 15 could be so formed that the flange 25 defining the locking groove 22 faces radially inward, rather than outward as described. In this event, a lobed circumferentially continuous ring in the then inwardly facing groove could effectively serve both to lock the wrist pins 18 against axial displacement and against rotational play.

It will be clear that I have described a simple, efficient, and readily installable means for securely locking wrist pins on a connecting-rod cluster in such a way that minimum wear of all parts will result. The locking means requires an absolute minimum of space and, with care, it may be reused in frequent overhauls of the engine.

Although I have described my invention in detail for the preferred form shown, it will be understood that modifications may be made within the scope of the invention as defined in the claims which follow.

I claim:

1. In a cluster for coupling a plurality of connecting rods to a crankshaft, a hub including a main body and a radially outwardly extending flange at each longitudinal end thereof, the outer diameter of said flange being less than that of said body whereby radially inwardly extending retainer-receiving grooves are defined between said body and said flanges, said hub including longitudinally extending wrist-pin-receiving bores through said body and through portions of said flanges whereby circumferentially spaced arcuate recesses are formed in said flanges, and wrist-pin retainers engageable in each of said grooves, each said retainer being circumferentially continuous and generally annular with a predominant inner diameter slightly in excess of the outer diameter of said flanges and having a plurality of radially inwardly extending arcuate projections circumferentially spaced about the axis of said retainer in accordance with the circumferential spacing of said bores, whereby one of said retainers may be axially inserted over a flange to a position substantially coplanar with one of said grooves, and further whereby said retainer may be locked between said flange and said body by a partial rotation thereof, said retainers including deformable portions deformable into recesses in said hub to secure said retainers in locked position on said hub.

2. In a cluster for coupling a plurality of connecting rods to a crankshaft, a hub including bayonet-locking means at one end and having a plurality of wrist-pin-receiving bores open at said end, a wrist pin in one of said bores and including a longitudinally extending projection more or less axially coextensive with said locking means, said projection being eccentric with respect to the axis of said wrist pin, circumferentially continuous wrist-pin-retainer means including a portion for engagement with said projection whereby said wrist pin may be secured against rotation about its axis, bayonet-locking means on said retainer means, whereby said wrist pin may be secured, against axial displacement

from said hub, said retainer means being deformable to lock said retainer means to said hub.

3. In a cluster for coupling connecting rods to a crankshaft, a hub including a radially extending flange defining a radially extending retainer-receiving groove, said hub having a plurality of longitudinally extending wrist-pin receiving bores through the body of said hub and through parts of said flange, whereby arcuate discontinuities are formed in said flange, the circumferential spacing of said bores to one side of a plane through an axis of symmetry intersecting the axis of said hub being substantially the same as the corresponding bore spacings to the other side of said plane, said hub including a first locking abutment means making with said plane a first angle about the axis of said hub and a second locking abutment means making with said plane and about the axis of said hub an angle substantially the image of said first angle, and a retainer ring having radial projections coinciding with said discontinuities, whereby said ring may

be inserted axially of said flange and rotated so that said projections may be engaged both by said flange and by the body of said hub, said retainer including a deformable portion deformable into engagement with one of said abutment means after said ring has been rotated into engagement with said flange.
